CLAIM

The ornamental design for a golf cleat wrench head, as shown and described.

DESCRIPTION

FIG. 1 is a front perspective view of a golf cleat wrench head showing my new design;

FIG. 2 is a partial first side elevational view thereof;

FIG. 3 is a rear elevational view thereof;

FIG. 4 is a second side elevational view thereof, perpendicular to FIG. 2; and,

FIG. 5 is a front elevational view thereof.

The subject matter shown in broken line represents unclaimed environmental structure which is shown for illustrative purposes and forms no part of the claimed design.
